UNITED STATES PATENT OFFICE.

WILLIAM J. LEVEY, OF SCHENECTADY, NEW YORK.

TROUSERS SUPPORTER.

Application filed May 12, 1925. Serial No. 29,772.

To all whom it may concern:

Be it known that I, WILLIAM J. LEVEY, a citizen of the United States, residing at Schenectady, in the county of Schenectady 5 and State of New York, have invented certain new and useful Improvements in Trousers Supporters, of which the following is a specification.

The invention relates to improvements in 10 trousers supporters.

The object of the present invention is to improve the construction of trousers supporters and to provide a simple, practical and efficient device of light, strong and durable construction adapted to be simply and effectively attached to the shirt and then connected to the trousers by slipping buttons of the trousers into slots in the device whereby the shirt will be held down and the 20 trousers supported in proper position without constricting the waist with a belt and also without the use of suspenders.

A further object of the invention is to provide a device of this character adapted 25 to be engaged with and remain on a shirt until the same is sent to the laundry and capable of enabling the trousers to be readily applied to it and of effectively preventing the trousers from becoming accidentally disconnected from it while in use.

With these and other objects in view the invention consists in the construction and novel combination and arrangement of parts hereinafter fully described, illustrated in 30 the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Figure 1 is a perspective view illustrating the manner in which the trousers are connected with the device attached to the shirt.

Fig. 2 is an enlarged rear elevation of the trousers supporter.

Fig. 3 is an enlarged front elevation partly in section of the same.

Fig. 4 is a central vertical sectional view through the trousers supporter and illustrating the manner of engaging the same with the shirt.

Referring to the drawing in which is illustrated the preferred embodiment of the invention, 1 designates a plate designed to be constructed of aluminum or other suitable material either metal, fiber, celluloid or the like and designed also to be slightly curved to conform to the configuration of the body of the wearer and connected detachably by means of spaced buttons 2 to the opposite sides of a pair of trousers 3 at the interior 60 of the same at the waist band as clearly shown in dotted lines in Fig. 1 of the drawing and connected also by means herein-after described to a shirt. The device after the buttons have been adjusted on the 70 trousers as hereinafter fully explained is engaged with the shirt and after the device has been properly adjusted to suit the wearer it is designed to remain attached to the shirt until the garment is laundered. 75

The plate 1 is oblong and is provided at the upper portion with horizontal longitudinal slots 4 terminating at their outer ends short of the ends of the plate and provided at their inner ends with enlarged entrance 80 portions 5 of sufficient size to permit the buttons 2 to pass readily through the slots for engaging the same with the plate 1. Portions of the slots lying beyond the enlarged inner ends 5 are of a width less than 85 the diameter of the heads of the buttons so that when the latter are engaged with the slots of the plate 1 and the trousers band is buttoned it will be impossible for the plate 1 to become accidentally disengaged from the 90 buttons. Safety buttons are preferably employed and have the usual metallic shank 6 so that there will be no liability of the plate cutting the shanks of the buttons. If the buttons are properly spaced so that the distance between them will not be greater than the distance between the outer ends of the slots 4 the trousers will not bulge when the buttons thereof are engaged with the device attached to the shirt. The heads of the buttons are passed through the enlarged portions of the slots and are moved towards the outer ends of the slots in attaching the band of the trousers to the device which has been previously applied to and is carried during 100 use by the shirt. When the band of the trousers is buttoned it is stretched and will present a smooth appearance and will not be loose or wrinkled between the buttons. 105

The plate is equipped at its lower por- 110

tion with a resilient clamping member 7 constructed of relatively heavy spring wire or similar material and provided at one end with a terminal eye 8 which is linked into a 5 loop 9 formed integral with the plate. The eye 8 is formed by coiling one end of the clamping member 7 and the loop 9 is formed by spaced openings 10. The portions of the plate between the openings 10 is bent or 10 bowed outwardly and the eye 8 is engaged with the same as clearly shown in Figs. 2 and 3 of the drawings. The other end of the resilient clamping member is free and is engaged with a keeper 11 consisting of a 15 tongue formed integral with the plate 1 the opposite side of the center from that at which the loop is located and the said tongue depends from the upper portion of an opening 12 and is bent outwardly with respect 20 to the plate 1 at the top to offset the said tongue from the plane of the plate. This will enable the free end of the clamping member 7 to be readily engaged with and disengaged from the tongue.

25 The clamping member is also provided with an intermediate engaging portion consisting of an inverted hook shaped loop 13 formed by bending the clamping member into an approximately U-shaped loop and 30 then curving or bending each side of the loop into approximately U-form to provide an inverted hook as clearly shown in Fig. 4 of the drawing for engaging a portion of the shirt to connect the device therewith so 35 that the weight of the trousers will be supported by the shirt and the shirt maintained in proper position by the weight of the trousers. This will distribute the strain incident to holding up the trousers over the 40 entire body of the shirt and will obviate the necessity of a belt and also the inconvenience and injury often resulting from the use of a tight belt or tight suspenders.

45 The plate is provided at the central portion with upper and lower apertures 14 and 15. The upper aperture is formed of an opening located between the enlarged inner ends 5 of the slot 4 and the lower aperture 15 consists of a relatively narrow longitudinal slot. In applying a device a portion 50 of the shirt is pulled through the lower aperture 15 and directed or folded upwardly and then passed through the upper aperture 14 and is engaged by the intermediate 55 clamping portion of the clamping member at the lower edge of the upper aperture as clearly shown in Figs. 2 and 4 of the drawing. After the intermediate engaging portion 13 of the clamping member is engaged 60 with the shirt, the free end of the clamping member is then engaged under the keeper formed by the depending tongue 11. A sufficient amount of the fabric of the shirt is 65 engaged with the plate 1 at the apertures 14 and 15 to prevent the garment from being

torn or worn through its engagement with the plate by the clamping member. After adjustment of the device to the garment has been properly made to suit the wearer the latter will become normal with the position of the device on the shirt and when transferring the device from a soiled shirt to a clean one the wearer will have become normal with the position of the device on the shirt and will be able to apply it to the shirt accurately without the measurement and adjustment originally required in first applying the device to a shirt. As the device is exceedingly inexpensive in construction a separate set may be conveniently employed 70 for each of several shirts in use so that in changing from a work shirt to a dress shirt or to any other type of shirt it will not be necessary to change the device from one shirt to another if each of the shirts is 75 equipped with a pair of the devices.

When the plate is constructed of fabric or other material, which may not have sufficient strength to enable the loop and the keeper to be formed integral with the plate 80 a rivet may be employed for securing the eye of the clamping member to such plate and the keeper may be formed by a separate piece of material suitably secured to the plate at an aperture similar to the aperture 12. A 85 metal keeper of this character may be readily riveted to a fiber or other plate where it is desirable to employ a metal portion to engage with the free end of the clamping member. 100

What is claimed is:

1. A trousers supporter comprising a plate provided at the upper portion with spaced longitudinal slots having enlarged inner portions for the passage of a button 105 and being of a width less than the diameter of the heads of the buttons beyond the enlarged portions, the plate having apertures located between the said slots and adapted to have a portion of a shirt passed through them, and a resilient clamping member carried on one side of the plate for engaging the shirt at the said apertures to clamp the shirt in said apertures and thereby secure the device to the shirt. 110

2. A trousers supporter comprising a plate adapted to be secured to the waist line of a pair of trousers and being relatively narrow with respect to its length so as to be worn by the wearer above the hips, the 120 plate having spaced apertures adapted to have a portion of a shirt passed through them and thereby wrapped around a portion of the plate, and a clamping member having a portion projecting through one of 125 said apertures for securing the device to the shirt.

3. A trousers supporter comprising a plate having an upper opening and a lower slot and adapted to have a portion of a shirt 130

pass through the slot and the opening, and a clamping member mounted on the plate and having a portion extending through said opening for clamping the shirt at the 5 said opening to secure the device to the shirt.

4. A trousers supporter comprising a plate provided intermediate of its ends with upper and lower apertures and adapted to 10 have a portion of a shirt passed through them, said plate being provided at one side of the apertures with a keeper and a clamping member connected to the plate at the opposite side of the apertures and engaged 15 with the keeper at one terminal portion, and a hook carried by the clamping member extending through one of the apertures for engaging the shirt at the apertures to secure the device to the shirt.
- 20 5. A trousers supporter comprising a plate provided intermediate of its ends with upper and lower apertures and adapted to have a portion of a shirt passed through them, said plate being provided at one side 25 of the apertures with a keeper and a clamping member connected to the plate at the op-

posite side of the apertures and engaged with the keeper at one terminal portion and provided with an intermediate engaging portion consisting of a loop bent to form 30 an inverted hook to extend through one of the apertures to engage the shirt at the apertures and thereby secure the device to the shirt.

6. A trousers supporter comprising a 35 plate provided with an aperture and having an integral loop at one side of the aperture and provided at the opposite side thereof with a depending tongue forming an inverted keeper and a resilient clamping member provided at one end with an eye linked into the said loop, the other end of the clamping member being detachably engaged with the keeper, said clamping member being also provided with an intermediate portion arranged to extend through said aperture and engage and clamp a shirt at the said aperture to secure the device to the shirt.

In testimony whereof I have hereunto set 50 my hand.

WILLIAM J. LEVEY.
